(57) CLAIM

The ornamental design for bottle, as shown and described.

DESCRIPTION

FIG. 1 is a front elevation view of a bottle showing our new design, the rear elevation view being a mirror image thereof; FIG. 2 is a right side elevation view thereof; FIG. 3 is a left side elevation view thereof; and, FIG. 4 is a top plan view thereof.

The broken lines shown in the drawing disclosure are for illustrative purposes only and form no part of the claimed design.
